CAR TRUCK

James A. Shafer, East Cleveland, Ohio, assignor
to National Malleable and Steel Castings Com-
pany, Cleveland, Ohio, a corporation of Ohio

Application October 25, 1940, Serial No. 362,747

4 Claims. (Cl. 105—197)

This invention relates to railway car trucks and has for an object the provision of a simple, yet effective, bolster supporting means adapted for use with either a bolster having cylindrical trunnions or a bolster equipped with trunnions having ends shaped so as to frictionally engage supplemental members located within the truck side frame.

Another object of the invention is to provide a supporting means for the bolster incorporating a strong and positive stop which will prevent the bolster supporting springs from going solid when subjected to an unusually heavy blow.

A further object of the invention is the provision of a car truck which may be inexpensively manufactured, and one in which worn parts may be readily and easily replaced.

Yet another object of the invention is to provide an oscillation damper consisting of bolster trunnions having ends formed with wedging surfaces which, when moved downwardly relative to the side frame, force friction shoes, having supplementary wedging surfaces, into friction engagement with a single renewable sleeve or bushing.

A still further object of the invention is the provision of bolster supporting means in which assembly is greatly facilitated by having each unit of the assembly positively position and lock in place the immediately succeeding unit.

Other objects and advantages of the invention will become apparent from the following description, taken in conjunction with the drawings, in which:

Figure 1 is a side elevational view, partly in section, taken on line 1—1 of Fig. 2, showing my invention adapted for use with a bolster trunnion having wedging surfaces thereon.

Figure 2 is a top plan view, taken on line 2—2 of Fig. 1, with one of the bolster trunnions and one set of friction shoes removed.

Figure 3 is a vertical sectional view, taken on line 3—3 of Fig. 1; and

Figure 4 is a partial view similar to Fig. 3, showing my invention adapted for use with cylindrical trunnions.

Referring to the drawings, the side frame 10 is formed with a tension member 11, a compression member 12, and connecting columns 13. The central portion 14 of tension member 11 consists of a bottom wall 15, side walls 16, and a top wall or shelf 17. In shelf 17 are located openings 18 through which springs 19, 20, friction sleeves 21, and friction shoes 22 are inserted into

the box-like housing 23 formed by walls 15, 16, and shelf 17.

The end 24 of truck bolster 25 is received in opening 44 of the side frame 10. On the under surface of bolster end 24, are downwardly extending trunnions 26 having two pairs of plane wedging surfaces 27, 28. The wedge shaped portions of the trunnions extend downwardly, through openings 18 in shelf 17 into frictional engagement with friction shoes 22.

Extending upwardly from shelf 17 to the under side of top wall 29 of bolster 25 are springs 30, 31, which acting in parallel with springs 19, 20, form a resilient support for the bolster 25.

Extending downwardly from shelf 17 into housing 23 are outer walls 42 and central wall 43 having shelves 32, 33 projecting inwardly towards springs 19, 20. A single friction sleeve 21, consisting of a major segment of a cylindrical bushing, is received in the opening 18, the upper surface of said sleeve being shown in the same horizontal plane as the upper surface of shelf 17. Shelves 32, 33 support the sleeve in its normal vertical position and prevent it from moving vertically downward. Upward movement of sleeve 21 is prevented by the overlapping of a portion of spring 30 with a portion of sleeve 21, as shown in Fig. 2. Rotation of sleeves 21 is effectively prevented by the columns 13.

Friction shoes 22 rest on springs 19, 20 and are partially encased by sleeve 21. Lugs 35 on the friction shoes prevent rotation of the shoes out of their correct position by engagement with ends 36 of sleeve 21. Each of the shoes 22 has a surface 37 curved to correspond to the inner curvature of sleeve 21. It will be noted that the curved shoe surfaces are made slightly sharper than that of the friction sleeve. This is done to cause the initial wear to occur at the central portion of the shoe along the line of action of the thrust from the wedge surfaces, thus eliminating any bending stresses in the shoes and also causing the shoes to wear until their surfaces substantially correspond to the inner surface of the sleeve. Opposite the curved surfaces 37 of the shoes are two plane wedge surfaces 38, 39 which are sloped so as to correspond to wedge surfaces 27, 28 on the ends of the trunnions.

Upon downward movement of the bolster relative to the side frame, friction shoes 22 are forced outwardly against friction sleeve 21 by wedge surfaces 27, 28 on bolster trunnions 26. The absorption of the energy of the movement quickly brings to a stop any oscillations of the springs, thus preventing subsequent shocks from building

up the amplitude of the spring oscillations to a point where damage might be done to the car lading.

The springs are prevented from going solid, in the event of an unusually heavy blow, by the engagement of the under surface 40 of the bolster with the top surfaces of shelf 17 and sleeve 21. In assembling my car truck, friction sleeves 21 are first inserted in the openings 18 and lowered onto shelves 32, 33. The sleeves are correctly positioned by the abutment of one of sleeve ends 36 with the column 13. Springs 19, 20 are then inserted into the housing 23. The friction shoes 22 are next placed in sleeve 21 and positioned by lugs 35 and sleeve ends 36. The bolster end 24 is then inserted in opening 44 and lowered until wedge surfaces 27, 28 on the bolster trunnions contact wedge surfaces 38, 39 on the friction shoes. It will be observed that in the assembly, each part is accurately positioned and locked in place by the part previously assembled, and that after a unit has been inserted, no further positioning of that unit is needed to enable the next unit to be properly positioned.

When one of the side frames of the car truck tends to run ahead of the other, such as the case would be in rounding a curve, one trunnion tends to slide up the wedge surfaces of one of the friction shoes, while the other trunnion tends to slide up the wedge surfaces of the shoe diagonally opposite the aforesaid shoe, causing a vertical displacement of the bolster and the car. As the trunnions rise on the one set of diagonally opposed shoes, the other diagonally opposed set is left free. Thus, when the force tending to keep the truck out of square is diminished, the weight of the car and bolster acting on the diagonally opposed wedging surfaces produces a couple which acts to bring the truck back into its proper alignment.

When it is desirous to use my invention with a cylindrical bolster trunnion 41, which is not equipped with the wedging surfaces for use with the friction shoes, it is necessary only to leave out the friction shoes and allow bolster trunnion 41 to rest on top of springs 19, 20, as shown in Fig. 4. The renewable friction sleeve 21 is kept in place and takes any wear that may be caused by the oscillating bolster trunnion 41. When used with the cylindrical trunnion, my invention affords the same protection to the springs, in case of oversolid blows, that it does when used with the friction type bolster trunnion.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. In a car truck, a side frame having a bolster receiving opening and a shelf therebelow, a bolster extending into said opening, bosses on said bolster extending downwardly through apertures in said shelf, resilient means positioned in said side frame below said shelf and in line with said apertures, a single friction member mounted

in each of said apertures, friction shoes disposed within said friction member and supported by said resilient means, lugs on said friction shoes adapted to cooperate with the ends of said friction member to prevent rotation of said friction shoes out of their normal position relative to said side frame, and wedging surfaces on said shoes adapted to cooperate with corresponding wedging surfaces on said bosses to force said shoes outwardly against said friction member upon downward movement of said bolster relative to said side frame.

2. In a car truck, a side frame having a bolster receiving opening and a shelf therebelow, a bolster extending into said opening, lugs on said bolster extending downwardly through apertures in said shelf, spring means positioned in said side frame below said lugs, a single friction member mounted in each of said apertures, friction shoes disposed within said friction member and interposed between said spring means and one of said lugs, wedging surfaces on said shoes adapted to cooperate with corresponding wedging surfaces on said lug to urge said shoes outwardly against said friction member upon downward movement of said bolster relative to said side frame, and means on said shoes adapted to cooperate with portions of said friction members to correctly position said friction shoes circumferentially of said friction members during assembly of said shoes with said members.

3. In a car truck, a side frame having a column and an aperture adjacent thereto, a friction member in the form of a major segment of a cylindrical sleeve received in said aperture and having its ends adjacent said column, a pair of friction shoes received by said friction member, spring means on said frame supporting said shoes, lugs on said shoes adapted to extend into the space between said ends of said member to assure correct positioning of said shoes circumferentially of said member during assembly of said shoes with said member, and a bolster having wedging surfaces adapted to cooperate with corresponding wedging surfaces on said shoes to urge said shoes outwardly against said member upon downward movement of said bolster.

4. In a car truck, a side frame having a bolster receiving opening and a shelf therebelow, a bolster extending into said opening, lugs on said bolster extending downwardly through apertures in said shelf, spring means positioned in said side frame below said lugs, a single friction member in the form of a major segment of a cylindrical sleeve mounted in each of said apertures, friction shoes disposed within said friction member and interposed between said spring means and one of said lugs, wedging surfaces on said shoes adapted to cooperate with corresponding wedging surfaces on said lug to urge said shoes outwardly against said friction member upon downward movement of said bolster relative to said frame, the radius of curvature of the surface of each shoe in engagement with said friction member being slightly smaller than the radius of curvature of the latter member so as to obtain initial engagement of the central portion of said shoe with said friction member.

JAMES A. SHAFFER.
